Patented Dec. 18, 1923.

UNITED STATES PATENT OFFICE.

MICHAEL M. SWEETMAN, OF KANSAS CITY, MISSOURI.

UNDERREAMER.

Application filed October 18, 1920. Serial No. 417,573.

To all whom it may concern:

Be it known that I, MICHAEL M. SWEETMAN, a citizen of the United States, residing at Kansas City, in the county of Jackson and State of Missouri, have invented certain new and useful Improvements in Underreamers, of which the following is a specification.

This invention pertains to underreamers for well drilling, and the structure is designed for use more particularly with deep wells where the soil is such that difficulty inheres in cementing the casing in its final position. Various structures have heretofore been devised and patented for underreaming, but difficulty obtains in the operation of such tools where a rotary drill rod has to be employed, for instance, in deep wells of Texas. Unless the underreamer can be made to properly perform its function and produce a chamber at the lower portion of the well into which the cement may flow, the wells may blow out.

The structure which forms the basis of the present invention is illustrated in the accompanying drawings wherein,

Fig. 1 is a vertical longitudinal section of the underreamer with the cutters shown in their extended operative position; and Fig. 2 a horizontal sectional view taken on the line II-II of Fig. 1.

In the drawing, 1 denotes the mandrel or stock of the tool having a box 2 formed at its upper end and a pin 3 at its lower end. Opening from the lower portion of the threaded box 2 is a cylinder 4 in which is mounted a piston 5. Said piston has attached to it a piston rod 6, the lower end of which is fashioned into a double-face rack 7 or the rack may be formed as a separate element and attached to the rod. The piston rod 6 passes downwardly through a chamber or bore 4^a which is a virtual continuation of the cylinder 4. A spring 8 resting at its lower end upon an inwardly projecting shoulder 9 and housed within the chamber 4^a, contacts the under face of the piston 5 and tends to elevate said piston and consequently to raise the piston rod 6 and the rack element. By-pass ports 10 are formed in the side wall of the lower portion of the cylinder 4 so that when the piston is in the position shown in Fig. 1 the water which is forced downwardly through the drill rod or tube will pass through said ports

below the piston and into the chamber 4^a, thence finding its way outwardly around the various elements, such as the cutters or bits 11 and 12. Said bits may be of any approved type. Each bit (the bits being duplicates) is mounted upon a pin 13 which extends through the body of the stock or mandrel 1. Said mandrel is provided with oppositely disposed slots 14 extending through the body thereof and in which slots the bits are mounted. Each bit is provided with a circular rack, as 15, which cooperates with the adjacent rack element of the member 7, so that as the rack is moved downwardly into the position shown in Fig. 1 the bits will be swung outwardly and as the rack is moved upwardly the bits will be rocked and swung downwardly passing into the slots 14 by which they are housed.

In operation a fish-tail cutter may be mounted upon the pin 3 in order to drill an extension of the hole, or if the hole is of sufficient depth, a suitable guide member of any form may be secured upon the pin. This arrangement acts to center and guide the tool. When it is desired to effect the underreaming operation the tool is placed upon the lower end of the drill stem and lowered to position. When it reaches a point where the bits or cutter blades 11 and 12 may be projected outwardly to begin the cutting operation, water under pressure is forced downwardly through the stem and into the cylinder 4. The pressure will force the piston 5 downwardly, placing the spring 8 under compression and forcing the bits ultimately outwardly and into the position shown in Fig. 1. Then through the manipulation of the drill stem the blades will be carried around and the undercut or reamed out chamber, as 16, produced. This chamber may be made of any desired depth and of any desired diameter, the latter being dependent solely upon the length of the bits. The pressure of the water is such that the piston will be held in its downward position so that the water will travel downwardly through the by-pass ports 10, through the chamber 4^a, around the piston rod 6, and outwardly through the slots 14, commingling with the soil which is loosened by the bits. Such mixture of water and soil, or, in effect, the mud, will be carried upwardly through the well casing, denoted by 17, and discharged as usual. When the under-

reamed opening or chamber has been made of sufficient size the water supply will be cut off, whereupon the spring 8 will exert an upward pressure to raise the piston and its attached parts and the rack will tend to swing the bits inwardly into the slots or openings 14. As the mandrel is drawn upwardly, and in the event the bits should stick, they will contact the lower end of the casing 17 and be forced downwardly into their closed position thereby, the curvature of the back 6 of the bits assisting in this action.

What is claimed is:-

15 In an underreamer, the combination of a mandrel provided with a cylinder in its upper portion and with a pair of oppositely disposed slots formed in the side wall there-

of adjacent its lower end; a piston mounted in the cylinder, said cylinder having bypass ports formed in the body of the mandrel to permit passage of water below the piston and outwardly through the body of the mandrel when the piston is forced downwardly by the water pressure; a bit pivotally mounted in each of the slots aforesaid; a gear formed upon each of said bits; a double face rack cooperating with the gears of the bits; a piston rod extending from the rack and connected to the piston; and a spring 20 25 30 located beneath the piston and serving to elevate the same when the water pressure is withdrawn therefrom.

In testimony whereof I have signed my name to this specification.

MICHAEL M. SWEETMAN.
